Perry W. Davis' Improved
Car-Coupling:

117992

PATENTED AUG 15 1871

UNITED STATES PATENT OFFICE.

PERRY W. DAVIS, OF PORTLAND, OREGON.

IMPROVEMENT IN CAR-COUPINGS.

Specification forming part of Letters Patent No. 117,992, dated August 15, 1871.

To all whom it may concern:

Be it known that I, PERRY W. DAVIS, of Portland, in Multnomah county, in the State of Oregon, have invented an Improved Car-Coupling; and I do hereby declare the following to be a full and exact description of the same, reference being had to the accompanying drawing making a part of this specification.

The drawing represents a vertical section through the center of the coupling, A and B being called "bumpers."

My invention relates to that kind of coupling known as a "pin-coupling," and opening and closing the pin of the same for the purposes herein specified. This coupling consists, essentially, of the four parts or pieces G, K, H, and E.

The operation of the device is as follows: The rear attachment A is provided with a spiral spring, E, which operates against the link F. The link F, being thrust against the pin C, is for a time held in check thereby, until the cam H is pushed under the incline on the piece G, which raises it to the position shown by the dotted lines at L. In the piece G the pin C is fixed. As the piece G rises it carries the pin C, and as soon as

the pin is raised the spiral spring E thrusts the link F under and beyond the pin C; and as soon as the forward bumper B advances the pin C falls in place inside the link F. For the purpose of uncoupling, when there is a strain on the pin C, the bent lever K is used. The short end is bent in the form of an eccentric centered on a pin, J, in the piece G; and the piece G is held in place by the pins C and I rising vertically on pin I.

From the above it will be seen that the coupling is self-acting and is easily uncoupled by the lifting of the lever K, be the strain great or small; and the hooking direction of the pin C augments the security against uncoupling, which cannot be done without raising the lever K.

I claim as my invention—

The draw-head A provided with the cam H, spring E, and link F, in combination with draw-head B provided with piece G, lever K, and pin C, substantially as described.

PERRY W. DAVIS.
